CLAIM

The ornamental design for a mobile phone shell, as shown and described.

DESCRIPTION

FIG. 1 is a top, front, right side perspective view of a mobile phone shell showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective of the mobile phone shell with the stand shown in an open state.

The broken lines show the features of the mobile phone shell that form no part of the claimed design.

1 Claim, 9 Drawing Sheets
